UNITED STATES PATENT OFFICE.

GEORGE WILKINSON, OF AURORA, ONTARIO, CANADA.

DESIGN FOR A PLOW-HEAD.

SPECIFICATION forming part of Design No. 19,111, dated May 21, 1889.

Application filed March 28, 1889. Serial No. 305,175. Term of patent 7 years.

To all whom it may concern:

Be it known that I, GEORGE WILKINSON, a subject of the Queen of Great Britain, residing at the village of Aurora, in the county of York, in the Province of Ontario, Canada, have invented and produced a new and original Design for a Plow-Head, of which the following is a specification, reference being had to the accompanying drawing, forming part thereof.

The drawing represents a perspective elevation of my improved plow-head.

The leading feature of my design consists of a plow-head curved from the point, the said plow-head being braced by a Y-shaped brace.

A represents the curved angle-steel plow-

head extending from near the end of the point B (shown in dotted lines) up onto the draw-head C, to which it is bolted, as indicated.

D is a Y-shaped brace bolted to the draw-head and designed to receive the landside.

I claim—

A plow-head angular in cross-section and curved from the point and braced by a Y-shaped brace, substantially as described and shown.

Toronto, March 9, 1889.

GEORGE WILKINSON.

In presence of—

CHARLES C. BALDWIN,
CHAS. H. RICHER.
